Qoo10 website, new Xiaomi Mi Air Purifier 2S sterilizer addition to Formaldehyde cleaning, Nov. 15, 2017 (Year: 2017).*

Primary Examiner — David G Muller*Assistant Examiner* — Nathan M Johnston(74) *Attorney, Agent, or Firm* — Calfee, Halter & Griswold, LLP(57) **CLAIM**

The ornamental design for an air purifier, as shown and described.

DESCRIPTION

FIG. 1 is a front view of the air purifier showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

The broken lines show portions of the design that form no part of the claimed design.

1 Claim, 7 Drawing Sheets(56)
